[57] ABSTRACT

This covers a control valve for a kitchen or like faucet embodying a cartridge or container housing two contiguous ceramic disk elements and a vertical rotary stem. One of the elements is positioned at the base of the stem and is a rotatable member while the other element is a stationary member upon which the rotatable member is slid. The stationary member has inlet and outlet ports both so arranged that, when the movable member is rotated about its axis through a limited angle, the movable member is rotated about its axis through a limited angle, the movable member will be rotatably slid over both ports of the stationary ceramic member to determine the relative sizes of the openings of both ports. Either hot water or cold water, whichever is fed to the inlet port, may be transmitted through the valve and the angular position of the movable member will alone control the volume of water flow through the valve. The slideable member includes a cavity having a plurality of steps or ridges positioned in the path of the water reaching the slideable member, and they reduce the noise level that would otherwise be developed upon water flow through the valve. The entire flow path within the valve is essentially free of parts which expand or contract to vary the flow as the water temperature changes. Each angular valve setting will correspond to a particular flow rate which may be changed as desired but will remain independent of changes in the water temperature.

CERAMIC DISK FAUCET

This application relates to control valves such as may be used in faucets providing hot and cold water to various plumbing fixtures, such as shower stalls or kitchen sinks or lavatories. The present invention is directed to an improved control valve that is superior in performance characteristics, ease of operation, ease of maintenance, and life span when compared to a conventional or so-called compression type of valve quite commonly and generally used for decades in faucets for plumbing fixtures.

This application discloses apparatus which is especially appropriate for use in a plumbing fixture employing a faucet coupled to two separate valves, each having a lever to control the hot and cold water, respectively, or a mixture thereof, supplied to the faucet of the plumbing fixture. In my Pat. Nos. 3,433,264 and 3,533,436, issued on Mar. 18, 1969 and Oct. 13, 1970, respectively, there are disclosed valve structures with ceramic discs which are actuated by a single lever that is tiltable and rotatable to simultaneously control the flow and mixture of hot and cold water emitting from the faucet. Faucets manufactured under or conforming to these cited patents have gained good acceptance for their convenience, trouble-free operation, and reliability. However, there are many users who prefer to keep the convention of having two independent control levers, rather than a single control lever, so that they may separately and independently control the hot and cold water supplies, and such users would also like to have the high performance and reliability and smoothness of operation of a valve structure, such as disclosed in the above-mentioned patents, which employ ceramic disks. The valve structure to be disclosed in this application fills that need and at the same time embodies additional features and qualities, as will be briefly explained hereinafter.

BACKGROUND OF THE INVENTION

In the conventional faucet for a plumbing fixture, or in a shower head, there is a handle on the left for controlling the flow of hot water and a separate handle on the right for controlling the flow of cold water. When both handles are manipulated, whether independently or simultaneously, the desired temperature of the exiting water delivered from the spout or shower head can be controlled, although often with great difficulty. In the conventional faucet, each control valve is composed of a handle-controlled rotary stem at one end of which a rubber-like or flexible substantially flat circular element, commonly called a seat washer, is affixed by means of a screw serving to hold the rubber-like (elastomer) seat washer element at the end of the stem. The control valve is equipped with a valve seat positioned upon and concentric with the input water port, the valve seat being stationary and positioned opposite the vertically movable rubber-like seat washer element. In the conventional faucet, by rotation of the stem, the rubber-like element may be moved vertically toward or away from the valve seat to close or open the water input port as may be desired. When the valve is to be closed, the handle-controlled stem is therefore rotated in one direction so as to advance the rubber-like seat washer element along its axis toward and against the valve seat which is usually positioned at the top of the input water port to seal the valve seat and its input

water port to cause the flow of water to be stopped. On the other hand, when the stem is rotated in the opposite direction, the rubber-like seat washer element becomes displaced from the valve seat along the very same axis so as to open the input water port and allow water to flow through the control valve to an output port. This type of mechanism, in which the rubber-like seat washer element is changed in its parallel spacing from the valve seat and from the input water port, is widely used in control valves to control the flow rate of the water through faucets which are parts of plumbing fixtures, such as sinks or lavatories.

There are many limitations and defects in the conventional control valve of the type just referred to. For example, the elastomer seat washer is subjected to considerable abrasive wear and this is due principally to the amount of mechanical pressure that is usually applied to the elastomer in closing and opening the valve. As the valve is closed, the elastomer seat washer, which is attached to the stem, is rotated with a twisting motion so as to drive the seat washer against the valve seat in attaining a good shut-off of the valve. This highly abrasive rotary or shearing motion causes wear both to the elastomer seat washer and to the surface of the valve seat which is usually metallic. In due course, the elastomer seat washer becomes worn down or cut away to render its surface uneven so that a good clean valve closure of the washer against the metallic valve seat may not be achievable. This usually results in difficulty in closing the valve and the difficulty necessarily increases with time. Greater mechanical pressure on the handle is then required to open and close the valve. Abrasion and wear are further magnified in localities where the water supply pressure is high because, in such areas, still greater forces are required to open or close the valve. This erosion also often results in leakage and wastage of water through the control valve due to the ridges and nicks developed in the washer and perhaps also in the valve seat. Because of this known inherent weakness of the control valve, too much pressure is customarily applied to the handle of the control valve to fully close the valve to prevent leakage and wastage of water. Users of the faucet, because of their past experiences with leaky faucets, tend to be heavy-handed and usually shut off the faucet with a manual force many times greater than is required and this further expands the wear and abrasion on the rubber seat washer and of the metallic valve seat. Experience abundantly reveals that, in the absence of sufficient closing pressure, the valve will indeed leak and waste water needlessly. The usual high manual pressure for mechanically closing the valve is ordinarily considered imperative to prevent the constant leakage and loss of water. It is because of this abnormal manual pressure customarily required to open and close the conventional valve that many people, especially children and old and infirm people, find it difficult, and sometimes impossible, to open the valve when they desire to start the flow of water and find it equally difficult to close the valve when water is no longer required. This constitutes a serious and long-standing difficulty with conventional water control valves for conventional plumbing fixtures.

Moreover, the rubber washer and the valve seat of the conventional control valve are often subjected to a number of environmental conditions that additionally shorten their lives. Commonly, sand or other foreign

particles are found in the water system and, when caught between the rubber washer and the seat, often become embedded in the rubber washer and scratch the valve seat as the faucet valve is closed. When a scratch or nick is made in the valve seat, more force is naturally required by the user to fully close the valve to eliminate leakage and a shortened life of the valve is inevitable. If a faucet having this type of valve structure is allowed to drip for a length of time, the pressurized water under relatively higher velocity in passing through a small nick in the valve seat will erode the seat in due course, causing the scratch or nick to enlarge. This causes a larger leak, quite naturally, and a correspondingly higher manual force on the handle will be required to avoid a dripping faucet when it is turned off. This is commonly known as wire-drawing of the seat. The sight of the leaky faucet is not uncommon in many places.

Besides the environmental problems of abrasive particles in a water supply, water in many areas contains chemical substances which corrode the common brass or bronze valve seat. Such corrosion shortens the life of the valve seat, whereupon the valve may have to be replaced in a period of time, perhaps six months.

Repairing a leaky valve in a conventional faucet is not an easy task for a homeowner and, at times, it is difficult or impossible even for a master plumber. After a conventional faucet is in service for some time, corrosion and liming combine to seize or lock the threads on various faucet parts. Difficulty can be encountered in removal of gland nuts, lock nuts, and screws holding the seat washers to the stems. Removal of the valve seat is usually not even attempted by the homeowner and, at times, this is found impossible even by the master plumber. Replacement of the entire faucet is costly, especially a bathtub faucet where part of a tile wall must sometimes be removed to install a new faucet. Furthermore, in the conventional compression type of valve produced for a shower head, the temperature-sensitive elastomer washer element will have a minimal dimension when the valve is closed or when cold water is received, but the element will expand when it is subjected to the elevated temperature of hot water. Hence, the size of the opening of the valve having such an expandable and contractable element in the control path will vary, depending upon the temperature of the incoming water. As the temperature rises and the elastomer element necessarily expands, the size of the water opening will be correspondingly reduced and soon reduce the amount of warm or hot water delivered through the valve. This can be especially uncomfortable in a shower stall because the temperature of the water will change even though the user intends to maintain the temperature substantially constant and therefore has not re-adjusted the valve. This constitutes another important deficiency in the common conventional compression type of valve and points up an added reason for effectively removing elastomer elements from essential flow paths or otherwise minimizing the difficulties that may be developed by their presence.

Other structural features of a conventional faucet also contribute to the difficulty in achieving the proper adjustment of the valve by the user to get the desired flow rate and the desired temperature of the water. For example, the normal looseness of the meshing stem threads causes variations in the valve opening, the magnitude of the variations usually depending upon

whether the handle of the valve is being adjusted toward its open position or toward its closed position. As the threads wear with use, this condition becomes more acute.

Many, if not all, of the above-noted difficulties have been plainly obvious throughout the decades, but very little has been done to remedy and obviate the difficulties which are ever present even in newly constructed homes.

SUMMARY OF THE INVENTION

Accordingly, a control valve has been achieved according to this invention which is virtually free of many, if not all, of the infirmities and difficulties of prior conventional mechanisms for plumbing fittings. The valve of this invention may be used interchangeably for either hot water or cold water, whether for kitchens or bathrooms. The present invention is, therefore, directed to a highly improved, simplified, long-lived, and relatively silent control valve which may be opened repeatedly or intermittently through a predetermined angle to establish a corresponding predetermined volume flow rate, and opened through another predetermined angle to obtain another corresponding predetermined volume flow rate, and closed, whenever desired, to completely shut off the flow of water. All of these improvements in the opening and closing of the valve of this invention may be accomplished with ease and without the employment of excessive manual or mechanical pressure and without damage to or destruction of any of the movable and stationary elements. This valve structure meets a long felt want, especially because it virtually eliminates the serious difficulties encountered in conventional water control valve for conventional plumbing fixtures.

In accordance with the present invention, the control valve includes a pair of hard contacting ceramic members, one of which is always stationary and entirely free of any motion, while the other member is controlled by a rotary stem which never moves axially, so that the other element is always in slidable contact with the stationary element to control the volume flow rate of the water. When the handle-controlled stem of the control valve is rotated for opening the valve, the slidable ceramic element will be slid along the surface of the stationary ceramic element and the slidable element may be moved over an angle which corresponds to the angle of rotation of the stem to achieve a predetermined opening of the valve port without changing the spacing or continuous contact between both ceramic elements. If the stem is rotated a bit further in the same direction, the valve port will be further opened by a proportional increment. On the other hand, when the stem is rotated in the opposite direction, the valve port will be substantially reduced in size to reduce the volume flow rate of water. When the stem is rotated further in the opposite direction through a sufficient angle, the valve port will be closed and there will be no further flow of water through the valve.

Thus, a rotational movement of the handle-controlled stem of the valve from its initial open position or its initial closed position will cause, for each individual angular rotation of the stem, a predetermined and corresponding change in the opening of the port of the valve. The proportionality of the changes in the flow rates will remain substantially the same in both directions of change. The mechanism will be substan-

tially free of wear and erosion for many years. Furthermore, the movement of the slideable ceramic disk in response to each rotational displacement of the stem of the valve can be achieved with the same relatively small torsional force applied to the stem and will not require the unusual and uneven torsional forces usually required in conventional valves to control such valves when they are to be opened or closed.

The two ceramic disks employed in and characteristic of this invention are enclosed in a common casing or cartridge and are expected to be used together for a very long time, perhaps twenty years, without requiring any re-adjustment or any maintenance service or any replacement of any of the parts. On the other hand, should a replacement or repair become necessary, the entire valve structure may be perfected merely by replacing the cartridge. This may be done by almost any unskilled person, so that the need for a plumber to make the valve replacement or repair will be unnecessary.

This invention, together with its objects and features, will be better and more clearly understood from the following more detailed description and explanation hereinafter following when read in connection with the accompanying drawing in which:

FIG. 1 illustrates an exploded view of the structure of the cartridge of the control valve mechanism of this invention;

FIG. 2 shows a perspective view of the structure of the general arrangement of this invention, this figure showing also an exploded view of the left end portion of the faucet;

FIG. 3 illustrates a front elevational view of the general arrangement of this invention, this figure also illustrating, in cross-section, part of the control valve structure;

FIGS. 4, 5, 6 and 7 illustrate schematically four different views of the two ceramic disk members corresponding to different angular positions of the movable ceramic disk member;

FIG. 8 shows a cross-sectional view of the two ceramic disk members taken along the line A—A of FIG. 7;

FIG. 9 illustrates two curves generally representing the respective forces required to manipulate the handle of a conventional faucet valve subjected to different pressures of the incoming water, and the handle of a faucet of the kind involved in the present invention and subjected to similar forces; and

FIG. 10 illustrates two curves comparing the flow rates of the conventional valve with the valve of this invention for different angular rotations of the handles of the respective faucet valves.

The same or similar reference characters will be employed throughout the drawing to designate the same or similar parts wherever they may occur in the drawing.

Referring generally to the drawing and especially to FIGS. 1 and 2 of the drawing which illustrate exploded representations of the control valve mechanism of this invention, and referring also to FIG. 3, the reference character CTG designates a cartridge which houses the two substantially parallel contiguous ceramic disks or elements DS1 and DS2 employed in this invention. The upper ceramic disk DS1 is rotatable about its center or axis and, in its rotation, is always slideable along the upper surface of the lower ceramic disk DS2 which is

and remains always stationary and immovable and is always held stationary and immovable. The upper disk DS1 is mounted within and held by projections SP1 and SP2 which are part of and integral with the structure of stem ST so that the upper disk DS1 is rotatable and slideable about its central or vertical axis. When the stem ST is rotated through any angular displacement for effecting a change in the flow rate through the control valve, the stem ST will necessarily rotate both the upper disk DS1 and the stem projections SP1 and SP2 which retain the upper disk DS1, through an equal and corresponding angular distance without causing the lower disk DS2 to be rotated or otherwise moved or changed in its position. Inasmuch as a sliding motion alone is involved between the two disks, the spacing between the two disks DS1 and DS2 will nevertheless remain unchanged throughout the sliding motion. The two disks DS1 and DS2 will be maintained in constant contact with each other although the upper disk DS1 may be rotated and slid into different angular configurations by various and different rotations of stem ST. The stem ST and disks DS1 and DS2 may be considered to have a common axis, but only the stem ST and the upper disk DS1 are revolvable, and they are revolvable as a unit through the same angle about the common axis by any rotation of the stem ST.

The lower disk DS2 is held fixed and immovable, both rotationally and axially or laterally, within the cartridge body BD by the rather wide projections PJ1 and PJ2 of disk DS2, the latter projections being held between the pairs of guiding projections GP1 and GP2 (see FIG. 1) on the inner wall of the cartridge body BD, as will be later explained. The lower disk DS2 is retained against downward displacement or movement by a cap CP which has two substantially equal openings CO1 and CO2 for water inflow and outflow, respectively. These openings CO1 and CO2 in cap CP are aligned with two corresponding counterbores CB1 and DO2 in the lower or stationary disk DS2 (see FIG. 1). The cap CP also embraces and supports two equal cylindrical seal rings SR1 and SR2 which may be made of any forms of elastomer or rubber-like materials and, as may be seen in FIGS. 1 and 3, they are sufficiently long so as to enter into, and be retained by, the two respective counterbores in the lower ceramic disk DS2.

The cap CP is positioned above the base nut BN which may be positioned immediately beneath the support SB which may be, for example, the platform of a kitchen sink, as shown in FIG. 2. An escutcheon ES serves as a trimming mounted above and about the base nut BN, as shown, the escutcheon ES also having aesthetic value.

A water inlet passageway IT and a water outlet passageway OT may be aligned with each other somewhat as illustrated in FIG. 3. These passageways IT and OT have neck portions TN1 and TN2. Water entering inlet tube or passageway IT will travel upward through the valve mechanism to the cavity in the upper disk DS1, then return via a down path in the valve mechanism, and then traverse the outlet tube or passageway OT to be exited by the faucet spout FT. The upper disk DS1 significantly has a fluid cavity but no fluid aperture or through passage.

It will be observed that each of the cylindrical seal rings SR1 and SR2 has a diameter which is appreciably greater than the opening of each of the neck portions TN1 and TN2 of passageways IT and OT, respectively.

Moreover, the rings SR1 and SR2 are longer than the overall vertical lengths of the two corresponding openings CO1 and CO2 of the CP and the respective counterbores CB1 and CB2 of lower disk DS2, as may be apparent from FIG. 3. Because of this significant geometry of the indicated components, any expected changes in the sizes of the elastomer rings SR1 and SR2 due to even wide temperature changes will not expand rings SR1 and SR2 so as to reduce or otherwise affect the rate of flow of water through either of the passageways IT or OT. Thus, the flow of water will be maintained rather completely independent of changes of the size of the elastomer rings SR1 and SR2 over any very wide temperature range that may be encountered in every day use of the valve mechanisms.

The base nut BN has an internally threaded section BTH above which may be applied a flat washer WS1. The nut BN and washer WS1 would be normally positioned beneath the support body SB. The internal threads BTH of nut BN would be joined to the external threads of the inlet supply shank 1SS. The shank 1SS will be coupled to the inlet water supply pipe SP as shown (see FIG. 3). The base nut BN may be rotated about the externally threaded segment of the shank 1SS so as to apply pressure between the base nut BN and the support SB through the washer WS1 to hold the base nut BN in a permanently stationary position and thereby hold the faucet against upward movement.

As shown in FIG. 2, a handle HN is mounted upon the stem ST and is affixed to the stem ST by a simple screw SC which is threaded into the upper serrated end of the stem ST. The opening within the handle HN will be brought down almost to the upper surface of escutcheon ES, as seen at the right of FIG. 3.

By rotating the handle HN in one direction or the other, the stem ST will be rotated through a corresponding angle to slidably rotate the upper disk DS1 on and about the upper surface of the lower disk DS2 without changing the spacing, and without affecting the intimate contact, between the disks DS1 and DS2. In other words, the ceramic disks DS1 and DS2 remain in firm contact with each other and the upper disk DS1 remains in slidable contact with the lower disk DS2 even though the upper disk DS1 is rotated to enlarge or reduce the effective sizes of the portal openings within the lower or stationary disk DS2, as may be desired, through which water may enter via the inlet IT and exit through the outlet OT to the faucet spout FT. In still other words, the rotation of the handle HN simply produces a rotational movement of the stem ST without changing the longitudinal position of the handle HN and without translatory movement of the stem ST and without changing the longitudinal position of the movable upper disk DS1 with respect to the stationary disk DS2. There is, therefore, no longitudinal movement of any of the parts of the cartridge CTG at any time, even while the volume flow rate of water is changed from time to time as desired by the user. A further feature is the continuous upward pressure exerted by the incoming water against the inner wall of the lower stationary disk DS2 acting to firmly hold the lower disk DS2 sealed against the upper disk DS1 while allowing the disk DS2 to be held stationary and allowing the upper disk DS1 to be rotated and slid, as often as desired, over the surface of the lower disk DS2 by rotation of the handle HN and of the stem ST by the user.

A washer WS2 (see FIG. 1) is mounted about stem ST above the shoulders or projections SP1 and SP2 of the stem ST and within the inner wall of the body BD of the cartridge CTG. This washer WS2 is preferably made of Teflon or a like material which will have a sufficiently low coefficient of friction so as not to retard or otherwise interfere with the rotary action of the stem ST when the handle HN is manipulated to change the flow rate. The washer WS2 serves as a thrust washer to prevent the upward movement of the stem ST in response to the pressure of the water received through the water inlet IT as the water travels through the two apertures of the lower disk DS2 and through the stepped cavity of the upper disk DS1 to be emitted by outlet OT (see FIG. 2).

As already explained, FIG. 1 shows the exploded view of the components of the cartridge CTG with the handle HN of the valve removed. The two retaining screws RS serve to maintain the cartridge CTG affixed to the faucet pad FP (see FIG. 2) in which there are two internally threaded openings to receive the screws RS. The threaded openings in pad FP serve to grip and hold the ends of screws RS.

FIG. 2 shows the relative positions of the retaining screws RS with respect to the cartridge CTG. When it is desired to remove the cartridge CTG, it is only necessary to remove the screw SC from the stem ST (within the handle HN) and then remove the two retaining screws RS, whereupon the cartridge CTG may be easily and quickly removed and replaced by another cartridge if this should be desired.

When the platform or support SB of a fixture, such as a sink, is to have the control valve installed, this can be easily accomplished merely by applying the washer WS1 and the base nut BN on one side of the support SB and joining the base nut to the external threads of the inlet supply shank 1SS. The water supply pipe SP may then be coupled to the inlet supply shank 1SS by means of a retaining or coupling nut CN, as shown in FIG. 3.

FIGS. 4, 5, 6 and 7 are views looking at the underside of the cartridge CTG, with the cap CP and the seal rings SR1 and SR2 removed. These views show the various openings of the inlet port DO1 and outlet port DO2 as the stem ST may be rotated to certain angular positions.

FIG. 4 shows the valve in its closed position, with wings SP1 and SP2 that project from shoulder SS on stem ST abutting projections GP1 and GP2 of body DB. It is noted that there is an appreciable distance between the edge of the inlet port DO1 of lower disk DS2 and the edge of the stepped cavity STP in upper disk DS1 which has no aperture or through passage for fluid transmission. Because the inlet port DO1 of the lower disk DS2 is spaced from the stepped cavity STP, no water can flow through the outlet port DO2.

FIG. 5 shows the shape of the port openings when the handle is positioned to provide a very low rate of flow through the faucet FT. The intersection of inlet port DO1 in the lower disk DS2 and the stepped cavity STP in the upper disk DS1 form a geometric shape that increases slowly and gradually during the first few degrees of opening effected by a small rotation of stem ST near the off-position. This provides "fine tuning" when low flow rates are desired. This also inhibits water hammer when the stem ST is returned to its closed position even when the handle HN is closed quickly.

FIG. 6 shows the port openings when the valve is placed in a "half-open" position. The inlet port DO1 in the lower disk DS2 is approximately 50 percent open and the outlet port DO2 in the lower disk DS2 is approximately 60 percent open. This throttling of the outlet port DO2 in relationship to the throttling of the inlet port DO1 in all partially open positions of the valve induces a back pressure in the stepped cavity STP in the upper disk DS1. This back pressure inhibits cavitation by reducing the number and size of cavitation bubbles that form as the water at high velocity passes through the inlet port DO1 into the cavity STP.

FIG. 7 depicts the valve in its fully open position. Note that both the inlet port DO1 and the outlet port DO2 are completely open to the stepped cavity STP and that the water cannot now be throttled at either port. Therefore, it can be seen that, because the outlet port DO2 is opened in conjunction with the inlet port DO1, this will not reduce the flow rate of the water in the fully open position of the cartridge CTG.

FIGS. 1 and 8 show the general contour of the steps in the non-apertured cavity STP of the upper ceramic disk DS1. The steps are five in number for illustration. The cavity STP within disk DS1 is bounded by the several steps therein and is part of the fluidic interconnection path for water received from the inlet conduit IT and transmitted through the outlet conduit OT. The sizes of the openings made available for water flowing into and out of the stepped region STP will be determined only by the angular displacement of the upper ceramic disk DS1. The space within the stepped cavity STP may be completely cut off from the inlet conduit IT merely by rotating the stem ST to one of its two extreme positions (see FIG. 4). On the other hand, coupling space within cavity STP will be brought to its greatest size when the stem ST is rotated about its axis to its other or opposite extreme position (FIG. 7).

The cavity embodying the five steps in the stepped region STP serves to provide a conduit between the inlet passageway IP and the outlet passageway OP (see FIG. 2) and the steps in the cavity also provide ridges for the substantial reduction or elimination of noise. It is a well known fact that cavitation will occur when the velocity of a liquid is raised sufficiently high so as to cause the pressure to drop to a very low level - a level approximating the vapor pressure of the liquid. Any substantial decrease in pressure often causes air bubbles to be formed and the bubbles grow in size until they reach a fluid zone of higher pressure. The developed higher pressure may be sufficient to burst the bubbles. The sudden collapse of the bubbles generates an undesirable but quite distinct audible noise. The edges of the ridges project into the fluid stream carrying the bubbles and act to divide or distribute the bubbles. The sharp ridges within cavity STP may cause the bubbles to be reduced in size or broken up. Hence, those bubbles that are not broken up are nevertheless prevented from growing large enough to cause excessive noise.

FIG. 8 shows an enlarged cross-sectional view of the two disks DS1 and DS2, especially magnifying the ridged region of the upper ceramic disk DS1. Each ridge may be regarded as having two semi-circular segments (see FIG. 7). Each segment includes parts of the several ridges and they have a common center as shown. Other parts of the ridges have a like common center. The line joining the two centers of the ridged

section is pitched at an angle, such as 21°, with respect to the normal vertical line as shown in FIG. 4. The two inner circular openings DO1 and DO2 of the lower disk DS2 provide the through paths for water flow. Water entering opening DO1 reaches the ridged cavity arena STP of the upper disk DS1, then turns around within the cavity of the upper disk DS1 and returns through opening DO2.

Two valves may be arranged on a sink or lavatory organized so that one of the inlet shanks IS1 may receive hot water and the other inlet shank (not shown) may receive cold water. The two outlet passageways OP may be connected by conduit OT to the faucet spout FT, as shown in FIG. 2, to receive and discharge both outputs as water of an intermediate temperature. The intermediate temperature will, of course, be fixed by the adjustments of the handles of the two valves.

While each control valve has been shown and described as having a lever handle HN to control the movement of its stem ST, the handle may be a circular handle or any other means for rotating the associated stem ST.

FIG. 9 presents a chart that shows the torques needed to operate the handle HN of the valve of the disclosed invention as compared to that needed to operate the handle of a conventional compression-type faucet valve. The torques needed to turn the handle HN are compared at the various inlet supply pressures that are commonly found in this country, the range extending from about 20 psi to about 120 psi. The marked lesser force required to adjust the valve of this invention will be readily apparent. The lesser required forces render the device of this invention operable by children as well as older or infirm people with equal facility. This is a distinct improvement.

FIG. 10 illustrates two curves drawn to compare a conventional valve with the valve of this invention as to the volume flow rate (in g.p.m.) with respect to the angular rotation of the handle HN of the valve from its "off" position. It will be readily apparent that the valve of this invention, when opened to start its flow, transmits water at a much slower rate of volume growth (see the dotted curve), but that the growth rate rises much more rapidly as the angular displacement is increased. Hence a finer control is obtained at the lower flow rates. This makes it easier for the user to select lower flow rates.

Both FIGS. 9 and 10 exemplify the surprisingly large advantages of the valve of this invention over conventional valve structures heretofore employed in plumbing fixtures.

The disks DS1 and DS2 are preferably made of an alumina ceramic material because such material has dimensional stability and its surfaces can be ground and polished to such a degree of flatness and smoothness that a liquid cannot pass between the contiguous surfaces. To effect the seal between the contiguous surfaces, a predetermined minimum contact pressure should be maintained to hold the surfaces in continuous abutting relationship even if one of the disks is to be slid over the surface of the other disk. The contact pressure is achieved without springs.

To effect the required seal, the seal rings SR1 and SR2 are made longer than the height of the apertures CO1 and CO2 within the cap CP that support the rings (see FIG. 1), so that the upper portions of rings SR1 and SR2 protrude into the enlarged cavities CB1 and

CB2, respectively, of the stationary disk DS2. Because of their lengths as already noted, the rings SR1 and SR2 will therefore be compressed, thereby exerting a continuous upward force against disk DS2. The upward force will hold the two disks together.

The seal of the mating surfaces of disks DS1 and DS2 remains effective continuously and is virtually independent of the inlet water pressure, however high or low it may be. Because of the low coefficient of friction between disks DS1 and DS2 and because of the presence of the Teflon washer WS2, the amount of torque required to operate the valve remains quite low even when the water pressure is relatively high.

Because of dimensional stability of the alumina ceramic disks, the handle HN may be moved to a desired position at different times and the volume of water flow through the valve will remain unchanged, notwithstanding changes in temperature of the fluid or in the environment or in the time intervals between the successive valve operations. The valve can therefore be rapidly brought to a position corresponding to a desired flow rate at any time. The valve may therefore be adjusted to a desired flow rate quickly and easily.

Because the ceramic disks DS1 and DS2 are harder than sand and other foreign materials found in water systems, the surfaces of the disks remain smooth and unscratched by foreign particles and are preserved in sealing, leak-proof condition for long periods of time. The intimate contact between such flat, highly polished surfaces precludes foreign matter from reaching the surfaces in contact with each other.

The valve cartridge CTG is self-contained and is easily replaceable by the homeowner without encountering the difficult problems usually facing the homeowner in repairing a conventional faucet. The faucet becomes operative anew immediately upon the replacement of the cartridge.

The disks DS1 and DS2 have been described as made of alumina ceramic materials. Such materials are preferred for the disk devices. The disk devices are readily made of such materials in large quantities and at relatively low cost, and their shapes can readily conform to precise dimensions. Such materials can be highly polished to provide easily slidable surfaces presenting minimal resistances. When so polished, leakage of water between adjacent disks becomes virtually nonexistent. However, other hard materials may be used in place of alumina ceramics. For example, metals such as stellite or tungsten carbides may be used for the disks, but such hard materials would be more costly to manufacture and, moreover, they do not provide the hardness and protection against sand particles conveyed by the water.

A Williams Pat. No. 3,009,679 issued Nov. 21, 1961, discloses a valve structure having, among other things, a valve seat of a graphite composition positioned on a water inlet passage, an O-ring mounted around the circumference of the valve seat to seal the valve seat from the inlet passage, a hard valve member rotatably mounted on the valve seat and affixed to a rotatable valve stem, and a spring seated on a shoulder within the inlet passage and pressuring the bottom of the valve seat against the valve member. The valve member embodies an eccentric port which may be aligned with another port in the valve seat. By rotating the valve stem, the ports are brought into alignment or registry or out of alignment or registry to control the flow rate through

the valve. This structure with its O-rings, its through ports in the adjacent valve seat and valve member, its biasing spring, etc., constitute a complicated valve of lesser value in manufacturing, maintenance and operating features than the simple distinctive cartridge valve of the present invention.

What is claimed is:

1. A faucet valve for controlling the rate of flow of fluid between a first conduit and a second conduit to be coupled to the valve, comprising first and second ceramic disks in contact with each other so as to have a common interface, the first disk having only two apertures for the flow of fluid, means in the valve to hold said first disk against rotation, said two apertures extending through said disk and coupled respectively to said first and second conduits, the second disk having an elongated unapertured cavity at the common interface of sufficient length and depth so as to provide the sole coupling between the two apertures, manually controlled means peripherally coupled to the second disk for slidably rotating the second disk about a single axis always perpendicular to the common interface for changing the position of its cavity with respect to both apertures and thereby adjusting the fluid flow rate, said manually controlled means including a substantially cylindrical rotary stem mechanically retaining the second disk at one end of said stem, said manually controlled means including means to prevent any motion other than rotary motion of the second disk and to prevent any change in the spacing between the two disks, and resilient means for applying pressure against one of the disks for continuously maintaining the two disks in physical contact with each other at the interface during all changes in pressure of the incoming fluid and during all rotations of the second disk.

2. A faucet valve according to claim 1 in which the manipulation of the stem controls only the angular rotation of the second disk, the valve including a substantially cylindrical collar within which the stem is confined so that the second disk is slidably rotatable solely about its axis.

3. A faucet valve according to claim 2 including a housing enclosing the first and second disks and the lower segment of the stem, the resilient means including cylindrical elastomer rings inserted within said apertures of said first disk to apply pressure to the first disk to maintain it in contact with the second disk at the interface, and a cap for supporting said elastomer rings and holding said elastomer rings against the first disk.

4. A faucet valve according to claim 3 including a handle coupled to the upper segment of the stem for manually imparting rotation to the stem.

5. A valve for the control of the rate of flow of fluid through a plumbing fitting, comprising a longitudinal non-rotatory stem which is rotatable and movable only about its axis without being movable in any other direction, a rotatable solid disk affixed to the base of said stem and rotatable through an angle corresponding to the angle of rotation of the stem and having a longitudinal fluid coupling cavity therein, a stationary solid disk having two parallel identical apertures therein for the flow of the controllable fluid therethrough, the rotatable disk being slidable along the adjacent surface of the stationary disk, means for applying pressure between the two disks for maintaining the two disks in continuous slidable contact with each other and inde-

pendent of the fluid pressure whenever the stem is axially rotated, the cavity of the rotatable disk being variably and adjustably alignable with the two apertures of the stationary disk and variably and adjustably disaligned with said apertures upon the axial rotation of the stem, the cavity providing the coupling between the two apertures to control the flow of fluid through and between said apertures, two conduits respectively coupled to the two apertures of the stationary disk, one of the apertures being supplied with pressurized water and the other aperture exiting the pressurized water received from the first aperture and transmitted through the cavity of the rotatable disk, said means for maintaining the two disks in continuous slidable contact including a housing having a collar within which the stem is guided to enable the stem to be moved only in rotation about its axis for holding the rotatable disk against movement other than rotary movement, and a stationary abutment means for limiting the angular rotations of the stem and the rotatable disk, said latter means comprising projections on said stem and corresponding curvatures about the rim of the rotatable disk.

6. A valve for the control of the rate of flow of fluid through a plumbing fitting, comprising first and second solid disks stacked together so as to be in continuous contact with each other, the first disk having a first aperture for the reception of fluid and a second substantially equal aperture for the discharge of the received fluid, an abutment means for holding the first disk stationary, the second disk having a cavity but no apertures, the cavity of the second disk fluidically coupling the two apertures to each other, a rotatable longitudinal stem the end of which has means to hold said stem perpendicular to the second disk to slidably rotate the second disk about its axis and along the adjacent surface of the first disk and to control the angle of slidable rotation of the second disk upon the surface of the first disk, the two disks being held in contact with each other throughout each rotation of the second disk, the valve having means to hold the stem non-movable longitudinally so as to maintain the surface contact between the two disks unchanged and to prevent any motion of the second disk except its rotary motion, whereby the rotation of the second disk in response to the rotation of the stem will control the volume of fluid flow from said first aperture through said cavity and exiting through said second aperture.

7. A valve according to claim 6, in which the cavity of the second disk is formed to have a plurality of steps having ridges for reducing the noise developed by the flow of fluid through the cavity.

8. A valve according to claim 7, including elastomer means for applying pressure between the two disks to maintain them in continuous contact with each other during the rotations of the stem and the second disk.

9. A valve according to claim 8, including a housing for enclosing and retaining the stem and the two disks in their respective positions, said housing providing the abutment means an abutment for holding the first disk continuously against any movement.

10. A valve according to claim 9 in which the disks are made of alumina ceramic material.

11. A valve according to claim 10 including a thrust washer interposed between the stem and the housing, said washer having a low coefficient of friction.

12. A valve for a plumbing fitting for the control of the rate of the flow of fluid through the fitting, compris-

ing a longitudinal stem which is rotatable about its axis but is not movable in any other direction along its axis, a first solid disk having a first aperture for receiving fluid and a second substantially identical aperture for discharging the received fluid, means for holding the first disk stationary, means for adjustably coupling the apertures of the first disk to each other to control the rate of flow of fluid between said apertures, said coupling means including a second solid disk having a cavity therein but no aperture so that fluid may flow from said first aperture through the cavity and out of the second aperture, said second disk having at least one projection which mates with a corresponding projection formed on one end of said stem so that, in response to any rotation of said stem about its axis, said second disk will slidably rotate about an axis and along the surface of the first disk to change the position of said cavity between the apertures of the first disk to control the fluid flow rate through the valve, and a stationary cylindrical collar within which the stem is rotatable to prevent any non-axial rotation of the stem and of the second disk.

13. A valve according to claim 12 including means supported beneath the first disk for continuously holding the first disk stationary, and for applying pressure against the first disk to hold it in continuous contact with the second disk throughout all rotations of the second disk.

14. A valve according to claim 13 including first and second elastomer cylindrical units which are larger in their external diameters than the diameters of the apertures of the first disk and are positioned between the first disk and the support means so as to be coaxially within the respective first and second apertures, said cylindrical units applying continuous mechanical pressure between the support means and the first disk.

15. A valve according to claim 14, including a housing for enclosing the two disks and the stem but apertured for exposing the upper end of the stem so that it may be manually rotated about a single axis to control the volume flow rate through the valve.

16. A valve according to claim 15, including a handle which is affixed to the upper end of the stem to be manipulated to control the rotary movement of the stem

17. A faucet valve for controlling the rate of flow of fluid between a first conduit and a second conduit to be coupled to the valve, comprising first and second ceramic disks in contact with each other so as to have a common interface, the first disk having two apertures extending through said disk and coupled respectively to said first and second conduits, the second disk having an elongated unapertured cavity at the common interface of sufficient length and depth so as to provide the sole coupling between the two apertures, manually controlled means peripherally coupled to the second disk for slidably rotating the second disk about a single axis always perpendicular to the common interface for adjusting the fluid flow rate without rotating the first disk and without changing the spacing between the two disks, resilient means for applying pressure against one of the disks for continuously maintaining the two disks in physical contact with each other at the interface during all changes in pressure of the incoming fluid and during all rotations of the second disk, said manually controlled means includes a substantially cylindrical rotary stem mechanically retaining the second disk at

15

one end of said stem to control the angular rotation of the second disk and also includes a substantially cylindrical collar within which the stem is confined so that the stem is slidably rotatable solely about the same axis, a housing enclosing the first and second disks and the lower segment of the stem, elastomer means inserted within said apertures of said first disk to apply pressure to the first disk to maintain it in contact with the second disk at the interface, a cap for supporting said elastomer means and holding said elastomer means against the first disk, and a handle coupled to the upper segment of the stem manually imparting rotation to the stem, the base of the stem and the second disk having projections for limiting the slidable rotation of the second disk and the angular rotation of the stem and for mechanically coupling both disks to each other.

16

mer means and holding said elastomer means against the first disk, and a handle coupled to the upper segment of the stem manually imparting rotation to the stem, the base of the stem and the second disk having projections for limiting the slidable rotation of the second disk and the angular rotation of the stem and for mechanically coupling both disks to each other.

UNITED STATES PATENT OFFICE
CERTIFICATE OF CORRECTION

Patent No. 3,810,602

Dated May 14, 1974

Inventor(s) Richard Grant Parkison

It is certified that error appears in the above-identified patent and that said Letters Patent are hereby corrected as shown below:

IN THE ABSTRACT -

Lines 9 and 10, delete the phrase "the movable member is rotated about its axis through a limited angle"

IN THE SPECIFICATION --

Column 1, line 37, delete "an" and insert --and--.

Column 9, line 57, delete "neverthesless" and insert --nevertheless--

Column 10, line 33, delete "childrem" and insert --children--; line 35, delete "rapidly" after period

IN THE CLAIMS --

Claim 5, Column 12, line 62, delete "for".

Claim 9, Column 13, line 60, delete "means for an abutment"

Signed and sealed this 13th day of May 1975.
